CLAIM

The ornamental design for a water filter as shown and described.

DESCRIPTION

FIG. 1 is a front elevation view of the water filter. The rear elevation view, which is not shown, is the same as the front elevation view.

FIG. 2 is a left side elevation view of the water filter. The right side elevation view, which is not shown, is the same as the left side elevation view.

FIG. 3 is a top plan view of the water filter.

FIG. 4 is a bottom plan view of the water filter.

FIG. 5 is a top perspective view of the water filter; and,

FIG. 6 is a bottom perspective view of the water filter. The broken lines in FIGS. 1-6 show unclaimed subject matter only and form no part of the claimed design.

1 Claim, 5 Drawing Sheets
